UNITED STATES PATENT OFFICE.

LOUIS G. WERNER, OF DES MOINES, IOWA, ASSIGNOR OF THREE-FIFTHS TO
M. C. FULLENWIDER AND JOHN W. CHASE, BOTH OF SAME PLACE.

CLIPPING-SHEARS.

SPECIFICATION forming part of Letters Patent No. 448,170, dated March 10, 1891.

Application filed March 26, 1889. Serial No. 304,910. (No model.)

To all whom it may concern:

Be it known that I, LOUIS G. WERNER, a citizen of the United States of America, residing at Des Moines, in the county of Polk 5 and State of Iowa, have invented an Improved Clipping-Shears, of which the following is a specification.

My invention consists in the construction and combination of an adjustable comb, a reciprocating cutter, and mechanism for transmitting and converting motion with a handle, as hereinafter set forth, pointed out in my claim, and illustrated in the accompanying drawings, in which—

15 Figure 1 is a bottom view of the handle, from which parts are broken away to disclose the mechanism for transmitting and converting motion combined therewith. Fig. 2 shows a piece of the handle and a swivel-joint connection between part of the operative mechanism and the handle. Fig. 3 is 20 a side view of the complete machine. Fig. 4 is a corresponding side view, from which parts are broken away to show the bell-crank 25 and cutter and a device for adjusting the comb. Fig. 5 is a perspective view of the machine.

A is a straight flat metal handle that has an integral concavo-convex enlargement B at 30 its front end adapted to inclose a bell-crank and to support a comb and a cutter. At its rear end it has an elbow-shaped enlargement C, adapted to support a rotating shaft. This shaft-support may be integral, as shown in 35 Fig. 1, or connected by means of a swivel-joint, as shown in Fig. 2, so that the handle can be more readily turned with the operator's hand as required to direct the cutter relative to the variable inclinations of the surface to 40 be traversed by the cutter.

d is a bell-crank pivoted in the enlargement B by means of a screw d', as clearly shown in Fig. 4.

d'' is a rotating shaft extended through a 45 bore in the extension C. It has a pulley f on its outer end and a crank f' on its inner end.

g is a rod that connects the crank f' with

the bell-crank d in such a manner that when the shaft is rotated the bell-crank will be vibrated. When the extension C has a swivel connection with the handle A, a universal joint g' is formed in the connecting-rod, as indicated in Fig. 2.

h is a cutter-plate of common form, that has 55 grooves h' in its top face that admit projections h⁴ at the corners of the enlargement B to enter and to guide the motions of the plate when it is reciprocated by the vibrating bell-crank, which has a projection i that enters a 60 corresponding opening in the top and center of the plate h.

m is a comb adapted in form to fit against and to close the open under side of the enlargement B, which enlargement has hooks 65 m' formed on or fixed to its edges in such a manner that the rear end of comb can be pushed over the hooks, so that they will hold the comb and also serve as fulcrums, upon which the comb can be adjusted as required 70 to regulate the friction of the sliding cutter-plate b.

r is a screw extended downward through a bore in the metal handle.

r' is a coil-spring in the bottom of the same 75 bore and under the end of the screw and in contact with the top of the rear end of the comb m. By means of the screw the pressure of the spring upon the comb can be readily regulated as required to control the 80 tension and friction of the reciprocating cutter.

s are wooden coverings fixed to the sides of the metal handle.

z represents a belt on the pulley f, through 85 which power and motion are transmitted from a suitable motor to rotate the shaft d, and thereby actuate the rod g as required to operate the cutter h by means of the bell-crank.

I am aware that clipping-shears have had 90 adjustable combs and tension devices and gearing combined therewith, thereby adapting them to be attached to and operated by a motor; but my manner of forming a handle with an enlarged recessed front end and a 95 tubular lateral extension at its rear end and

combining a bell-crank, a cutter, a comb, and a rotating shaft therewith is novel and greatly advantageous.

I claim as my invention—

5 The handle B, having a recessed enlargement at its front end, a pivoted bell-crank d in said enlargement, a lateral extension C, swiveled to its rear end, a rotating shaft f,

having a crank on its inner end, and a rod g, having a universal joint g', arranged and combined in a clipping-shears, substantially as shown and described, for the purposes stated.

LOUIS G. WERNER.
